W. M. RIGGINS

RAIL CLAMP AND BRACE

Filed Feb. 14, 1924

Inventor
William M. Riggins,

By Attorney

Patented Oct. 14, 1924.

UNITED STATES PATENT OFFICE.

WILLIAM M. RIGGINS, OF AUSTINVILLE, VIRGINIA.

RAIL CLAMP AND BRACE.

Application filed February 14, 1924. Serial No. 692,831.

To all whom it may concern:

Be it known that I, WILLIAM M. RIGGINS, a citizen of the United States, residing at Austinville, in the county of Wythe and State of Virginia, have invented new and useful Improvements in Rail Clamps and Braces, of which the following is a specification.

The invention relates to a rail clamp and brace.

The object of the present invention is to provide a simple practical and efficient rail clamping and supporting member designed to be fixed to a metallic cross tie and to fit against the rail at the bottom flange, the web and the ball or head for holding the same firmly upon the cross tie and for also bracing the rail and preventing the same from rolling outwardly or spreading. A further object of the invention is to provide a device of this character and a cooperating movable inner rail engaging member or clamp adapted to maintain the rail firmly in engagement with the fixed outer clamp and provided with means for engaging the rail at the flange and web and head or ball and to firmly brace the same. Another object of the invention is to provide an inner rail clamp adapted to be readily turned into and out of engagement with the rail to enable the latter to be easily and rapidly applied to and removed from a cross tie.

Another object of the invention is to provide a reinforcement member adapted to be arranged between the converging rails of a switch or frog and adapted to engage the bottom flange web and head or ball of the rail for firmly bracing and supporting the same.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings, in which like characters of reference designate corresponding parts in the several views:

Figure 1 is a plan view of a portion of a railroad track provided with rail clamps and reinforcement members constructed in accordance with this invention.

Figure 2 is a side elevation of the same. 60

Figures 3 and 4 are detailed perspective views of the inner and outer rail clamping members.

Figure 5 is a plan view of the reinforcement member. 65

Figure 6 is a reverse plan view of the same.

In the accompanying drawing in which is illustrated the preferred embodiment of the invention, 1 and 2 designate inner and outer rail clamping members mounted upon a metallic rail tie 3 constructed of steel or other suitable material and preferably consisting of a flat horizontal body, but any other desired form may be used. 75

The outer rail clamping member which is constructed of suitable metal, comprises a lower base portion and upper and lower projecting arms 4 and 5 formed integral with the base portion which is rigidly secured to the cross tie by rivets 6 or other suitable fastening devices. The rail clamping member is provided at the lower face with a recess 7, formed by the lower face of the lower projecting arm 5 and located above the plane of the lower face of the base portion and conforming to the configuration of and adapted to receive the bottom flange of a rail 9. The lower integral projecting arm 5 fits against the upper face 90 of the bottom flange and extends to the web 10 of the rail 9 and it has an inclined upper face 11. The integral upper arm 4 is arranged at an inclination and it fits against the underside of the head or ball 95 of the rail in the angle formed by the same and the web 10. The inner and outer faces of the upper arm 4 are inclined and the upper end is beveled at 12 to form a shoulder to fit against the underside of the head 100 of the rail and it is also provided with an end face 13 which fits against the web of the rail contiguous to the head thereof. The outer clamping member firmly engages the rail and braces and supports the same and prevents the rail from rocking or rolling outwardly or otherwise spreading. 105

The inner clamping member 1 comprises a base portion and an arm 14 forming a lower recess 15 to receive the adjacent bot- 110

tom flange of the rail. The arm 14 fits against the web of the rail at the inner side of the same and it terminates short of the head of the rail so as to lie beyond the flange of a car wheel. The base of the inner clamping member is pivoted at 16, by a bolt, rivet or other suitable fastening device and it is detachably secured between its end face 17 and the pivot 16 by a removable bolt 18 which is adapted to hold the inner rail clamping member firmly in its engaging position in contact with the rail. The engaging end face 17 of the inner clamping member is bevelled or cut at an angle to form a tapered or wedge shaped arm which is adapted to be swung into tight engagement with the rail for holding the same firmly in engagement with the outer rail clamping and bracing member 2. The inner rail clamping member is adapted, as illustrated in dotted lines in Figure 1, of the drawing, to be readily swung out of engagement with the rail to permit the removal of the rail.

The metallic cross tie is also equipped with a reinforcing member 19 consisting of a substantially horizontal body portion and upwardly extending tapering lugs or arms 20, which fit against the inner opposed faces of the webs of the converging rails 21 of a switch or frog. The arms or lugs 20 have their lower faces arranged above the lower face of the reinforcement member to provide end recesses 22 for the reception of the inner bottom flanges of the rails 21 and the base or body portion of the reinforcement member has a tapered enlargement 23 located between the said recesses 22 and fitting between and conforming to the configuration of the adjacent side edges of the bottom flanges of the converging rails.

The lugs or arms 22 fit against the upper faces of the bottom flanges of the rails and against the webs thereof and under the heads of the same, and the reinforcement member is tapered or wedge shaped in plan view to conform to the configuration of the angularly disposed rails 21. The reinforcement member is secured to the cross tie by means of a bolt 24, which maintains the reinforcement member rigidly in position with its angularly disposed end faces 25 in firm engagement with the rails 21.

Instead of beveling both ends of the re-

inforcing member 19, one end may be cut square as shown at 20^a in Figure 1.

What is claimed is:

1. A device of the class described including an outer rail bracing member comprising a base, and integral upper and lower relatively long angularly disposed rail engaging arms, the lower rail engaging arm being arranged in a substantially horizontal plane and spaced from the plane of the lower face of the bottom member to form a recess to receive the bottom flange of a rail and fitting against the same from the outer edge thereof to the web of the rail and also against the said web, the upper portion being inclined and fitting against the web contiguous to the head of the rail and also against the under side of the head of the rail and an inner clamping member comprising a pivoted base and a wedge shaped arm carried by the base and movable into and out of engagement with the bottom flange and web of the rail, and a removable bolt located at the inner side of the pivot and piercing the said base for rigidly maintaining the inner member in engagement with the rail.

2. A device of the class described including a reinforcement member designed to be arranged between adjacent angularly disposed rails of a frog or switch and comprising a relatively thin continuous body portion, and upwardly extending lugs projecting above the plane of the lower face of the body portion and forming end recesses and an intermediate extension, the end recesses being arranged to receive the bottom flanges of the said rails and the said extension being tapered or wedge shaped to fit the edges of the bottom flanges of the rails, said lugs engaging the upper faces of the bottom flanges of the said rails and also engaging the webs of the rails from the bottom flanges to the heads thereof, and supporting the latter and a removable bolt piercing the body portion of the device between the lugs and rigidly securing the said device in position.

In testimony whereof I have hereunto set my hand.

WILLIAM M. ^{his} X RIGGINS.
